FIG. 1 is a plan view of an embossed tissue in accordance with this invention; and,

FIG. 2 is an enlarged fragmentary cross-sectional view of the tissue of FIG. 1 taken along line 2—2.

The side and bottom surfaces of the embossed tissue form no part of the claimed design.

The embossed tissue is shown cut away on each of its four sides to indicate indeterminate length and width. The broken lines in FIG. 1 depict one repeat unit of the embossed tissue, which repeats uniformly throughout the length and width of the embossed tissue. The broken lines form no part of the claimed design.
